BY HIS ATTORNEYS,

Higdon & Higdon

UNITED STATES PATENT OFFICE.

WILLIAM H. SMITH, OF BLYTHEDALE, MISSOURI.

SEALED LEG-BAND.

SPECIFICATION forming part of Letters Patent No. 664,062, dated December 18, 1900.

Application filed March 8, 1900. Serial No. 7,920 $\frac{1}{2}$. (No model.)

To all whom it may concern:

Be it known that I, WILLIAM H. SMITH, a citizen of the United States, and a resident of Blythedale, in the county of Harrison 5 and State of Missouri, have invented certain new and useful Improvements in Sealed Leg-Bands, of which the following is a specification.

My invention relates to improvements in sealed leg-bands for poultry, pigeons, &c., and aims to provide a band for the labeling of poultry, pigeons, or other birds which shall be of simple and cheap construction, easy of application to the bird, and so formed that 15 when once in position on the bird's leg it will be impossible to remove it without destroying the band.

In the drawings, Figure 1 is a perspective view of the band in normal form before being applied to the bird's leg. Fig. 2 is a horizontal section through the band after being bent up in ring form, but not yet secured. Fig. 3 is a perspective view of the band after being bent up in ring form and partially secured. 25 Fig. 4 is a top plan view of the band in ring form fully secured and sealed. Fig. 5 is a similar view taken on the side opposite to that shown in Fig. 4.

The band is formed of a strip of sheet metal 30 1, as shown in Fig. 1, of suitable length to fit the leg of the bird to be marked. Said strip is provided near one end with a pin 2, of soft metal, which is passed through the body of the strip 1 and riveted on the side which is to 35 form the inner side of the band, as shown in Fig. 2. At a suitable distance from pin 2 an opening 3 is punched in the material, leaving, however, a projecting tongue 4, still integral with the body of the strip. At the opposite 40 end of said strip two openings 5 6 are formed

therein, the outer one, 6, being adapted to engage the tongue 4 when the strip is bent up around the bird's leg and the inner one, 5, to engage at the same time the pin 2, as seen in Fig. 2.

The strip having been applied to the bird's leg in the manner stated, the tongue 4, protruding through the opening 6, is bent over and clenched on the outer surface of the band, and the pin 2, projecting through the opening 5, is subjected to pressure by a pair of pincers or other similar implement, by which pressure said pin is flattened and at the same time, if desired, impressed with any suitable inscription, symbol, or mark. After such 55 pressure has been applied to the pin 2 it is no longer possible to withdraw it from engagement with the opening 5 without breaking off said pin, and the device is therefore effectually sealed.

Having thus described my invention, what I claim as new, and desire to secure by Letters Patent, is—

A leg-band for birds or poultry, consisting of a strip of sheet metal 1, having two openings 5 and 6 through one end thereof, an integral tongue 4 at the other end thereof adapted to pass through one of said openings, and a soft-metal pin 2 riveted to said strip near tongue 4 and adapted to be inserted in one 65 of said openings and spread or flattened over the edges of said opening so as to form a seal bearing an impressed figure or letter, substantially as described.

In testimony whereof I affix my signature 70 in the presence of two witnesses.

WILLIAM H. SMITH.
